(57) **CLAIM**

The ornamental design for a medicament delivery device cover, as shown and described.

DESCRIPTION

FIG. 1 is a front view of a medicament delivery device cover;

FIG. 2 is a front perspective view of the medicament delivery device cover;

FIG. 3 is a rear perspective view of the medicament delivery device cover; and

FIG. 4 is a top left perspective view of the medicament delivery device cover.

In the drawings, the dashed lines (- -) depict portions of the article that form no part of the claimed design. The relatively light shade lines on the surface portions indicate contour, not surface decoration, and form no part of the claimed design. The dot-dash broken lines define the bounds of the claimed design and form no part thereof.
